UNITED STATES PATENT OFFICE.

ARTHUR L. MOORE, OF SPRINGFIELD, MASSACHUSETTS.

BOLT-CLIPPER.

No. 806,481.

Specification of Letters Patent.

Patented Dec. 5, 1905.

Application filed April 24, 1905. Serial No. 257,234.

To all whom it may concern:

Be it known that I, ARTHUR L. MOORE, a citizen of the United States of America, and a resident of Springfield, in the county of 5 Hampden and State of Massachusetts, have invented certain new and useful Improvements in Bolt-Clippers, of which the following is a full, clear, and exact description.

This invention relates to improvements in 10 bolt-clippers of the class comprising compound levers, one pair thereof constituting the handle or operating members and the other carrying the cutters or bolt-clipping dies.

15 The particular object of this invention is to provide a clipper having adjustably-movable members or levers for positioning the cutter-levers to compensate for wear or grinding away of the cutters and having combined therewith means not only for moving the adjusting-levers with great power and for exactness of adjustment, but for also effectually maintaining the parts located in their 20 adjusted relations, and an important object 25 also attained is the production of a clipper having the capabilities stated and constituted by a reduced number of cheaply and simply constructed and easily-assembled parts; and the invention consists in the constructions 30 and combinations or arrangements of parts, all substantially as hereinafter fully described, and set forth in the claims.

In the accompanying drawings, Figure 1 is 35 a side view of the present improved bolt-clipper, portions of the long handles of which are represented as broken away and the portions of said handles shown as broken out and in vertical section. Fig. 2 is a perspective view of certain parts of a bolt-clipper 40 comprised in this invention as in separated relations to each other.

Similar characters of reference indicate 45 corresponding parts in both of the views.

In the drawings, A A represent the "handles," which are of considerable length and united at their forward angularly-turned extremities by a hinge-pivot a. A semicircular sidewise-open recess or depression B is formed 50 in each handle A adjacent the hinge-pivot a, such recess being the counterpart in circumferential dimension of the shouldered intermediate portion of each of the pair of adjusting-levers C. The adjusting-levers C, which are 55 pivotally held in position in the recesses B by the pivot-bolts b, have each on one arm c thereof the ear-lugs c', between which the reduced

extremities of the free ends of the cutting-jaw levers D are engaged and held by the bolts d. The cutting-jaw levers D are held in pivoted relations to each other by the usual side links 60 E, which are pivotally connected thereto by their pivot-bolts e e. The arms G endwise opposite to those above mentioned of the adjusting-levers C extend into the cavities H, which are formed in the handles and extend 65 thereinto from the handle depression B in a direction toward the free ends of said handles a considerable distance, as shown by a reference to Fig. 1. The free ends of the arms G of adjusting-levers are constructed 70 with the gear-teeth g arranged in radial relation to the pivot-bolts b, thereby constituting segmental worm-gears g.

At a point in each handle-cavity H near its closed end is located a vertically-supported screw-threaded bolt or worm I, its shouldered end portions h and h' having bearings in the outer and inner edge walls of the said cavity in the handle. The shouldered end h' enters and is supported in the round hole j of 75 the handle, and the shouldered end h has a bearing in a nut K, which nut has a screw engagement within the threaded hole k of the handle, and this hole k is of a diameter equal to that or larger than that of the worm I, 80 thus permitting the positioning of the worm I in the handle-cavity H, whereby the subsequent positioning of the adjusting-lever C brings the segmental gear G of the same into mesh with the worm I. 85

A squared portion i² of the shouldered bearing end h of the worm I is adapted to be engaged and turned by a wrench, whereby the rotation of the worm I rocks the adjusting-lever C on its pivot b by its engagement therewith of the segmental gear G, to the end that the cutting-jaw levers D, having the cutting-jaws D' thereon, are correspondingly moved or adjusted to the handles A through the pivot engagement of adjusting-lever arm c 100 therewith. The powerful action of worm and segmental worm-gear wheel constructions combined with the natural lock against inadvertent rotation that they possess render this means for imparting the desired 105 rocking movement for adjustment purposes to the adjusting-lever C an unusually desirable one by reason of the capacity for great strength in the parts and of their cheapness of construction, durability, and capability 110 for withstanding protracted use without impairment.

Having thus described my invention, what I claim, and desire to secure by Letters Patent, is—

1. In a bolt-clipper of the class indicated, 5 the combination with the handle-levers pivotally jointed at their forward extremities, the cutter-levers and adjusting-levers jointed to the cutter-levers and intermediately pivotally jointed to the handle-levers adjacent to the handle-lever hinge-joint, and having their rearwardly-extended arms formed with worm-segments at their ends, and worms supported for rotary movement on, and arranged transversely of the handle-levers, in 15 engagement with the worm-segments, and having provisions for imparting their rotational movements to the adjusting-levers.
2. In a bolt-clipper of the character described, the combination with the handle-levers pivotally jointed at their forward extremities, and having a sidewise-opening recess B with partially-circular edge walls and said handles having longitudinally-extending cavities H, H, opening to said recesses, of 25 the cutter-levers D D and the adjusting-levers C C having the thickened and rounded intermediate portions fitted in said recesses B, and pivotally connected thereat with the handle-levers, and having their arms G rearwardly extending into said handle-cavities and provided at their ends with the worm-segments g, and the worms I I journaled within the walls of the handle-levers, traversing the cavities therein, and in engagement 30 with the worm-segments of the adjusting-levers.
3. In a bolt-clipper of the character described, the combination with the handle-levers pivotally jointed at their forward extremities, and having sidewise-opening recesses B with partially-circular edge walls and said handles having longitudinally-extending cavities H, H, opening to said recesses, and constructed with the journal-hole j at one edge wall, and with the comparatively large threaded hole k through its opposite edge wall, of the cutter-levers D D and the adjusting-levers C C having the thickened and rounded intermediate portions fitted in said recesses b, and pivotally connected 45 thereat with the handle-levers, and having their arms G rearwardly extending into said handle-cavities and provided at their ends with the worm-segments g, and the worms I I, having the inner end journals h' fitted in said holes j positioned transversely of the handle-lever and with their threaded portions within the cavities thereof and in engagement with the adjusting-lever worm-segments, having the outer and round journal portions 50 h, and the squared extremities i, and the nuts K, screw-engaged in said holes k and having axial journal-holes for the said journal portions h of the worms, substantially as shown.

Signed by me at Springfield, Massachusetts, in presence of two subscribing witnesses.

ARTHUR L. MOORE.
